DIRECTIONAL SIGNAL

William P. MacMicking, St. Petersburg, Fla.

Application May 20, 1938, Serial No. 208,992

3 Claims. (Cl. 116—39)

My invention relates to improvements in directional signals, especially such as may be used in connection with vehicles.

An object of my invention is to provide a signal for vehicles which can be readily observed and attract attention thereby conveying notice of intent of the operator to turn in an indicated direction.

A further object of my invention is to provide a power actuated signal controllable by a vehicle operator whereby direction of turn is indicated by a continuously rotating signal, the direction of rotation indicating the proposed direction of vehicle turn.

No doubt other objects coherent with my invention will present themselves during consideration of the drawings, specification, and claims.

I attain these objects by mechanism illustrated in the accompanying drawings, wherein—

Figure 1 is a front elevation with the signal extended in operating position.

Figure 2 is a sectional view on the line 2—2, Figure 1.

Figure 3 is a sectional view on the line 3—3, Figure 1.

Similar reference characters refer to similar parts throughout the several views.

Referring more particularly to the drawings which illustrate my preferred form of construction 6 indicates the signal member proper which may be of any conventional type which will attract attention. A piston rod 7 supports said signal 6 on its outer end and is engaged at its inner end to a piston 9 within a cylinder 10.

Suitably located and communicating with said cylinder are tubes 11 and 12 same being adapted to convey motive fluid such as air or gas to the opposite end portions of the cylinder to permit the extending or retracting of the signal, the source of said motive fluid and provided passages for same to said tubes being hereinafter described.

The motive fluid, air or gas, may be derived through communication with the intake manifold of an engine, or from any other suitable and desirable source, and directed by means of a tube 13 to a directional control valve 14. Through the use of said direction control valve 14, which is conveniently located within the vehicle and which may be of any conventional type which may be suitable to properly direct the motive fluid into the proper passage leading to the cylinder depending on the desire of the operator to extend or retract the signal or shut off all passage.

Communicating with said control valve and extending therefrom to the signaling device at their opposite ends are tubes 15 and 16 to provide passage for the motive fluid from the control valve to the signaling device and thence through hereinafter described passages to the cylinder 10.

Forming a part of said signaling device is a plate member forming an arm 17 within which are longitudinal parallel passages 18 and 19, the lower ends of which are communicated with the tubes 15 and 16. Extending horizontally therefrom and on the inner face thereof is a stub shaft 20 within which are passages 21 and 22 which respectively communicate with passages 18 and 19, the outlet for said passages 21 and 22 being orifices 23 and 24 respectively, orifice 23 being at the rear side of said shaft and orifice 24 at the outer side portion of said shaft thereby providing communication with a coupling member while same is rotated as hereinafter described.

Rotatably mounted on said shaft 20 is a spur gear 25 upon the outer face of which is rigidly fitted the cylinder 10. Extending through said gear 25 are orifices 26 and 27 respectively communicated with tubes 11 and 12.

Intercentral said arm 17 and spur gear 25 is a coupling 28 having one face thereof in impervious engagement with said gear to rotate therewith, and imperviously engaged on the opposite face of said coupling is a cap c. Within the opposite faces of said coupling 28 are routed portions forming cylindrical passages 29 and 30, each of which has an orifice outward from the outer periphery of said passage, thereby providing constant communication between orifices 23 and 24 and orifices 26 and 27 respectively, the prime purpose of said coupling being to assure an unobstructed passage for the motive fluid while the signal is rotating.

To provide rotating means for the spur gear 25 in either a clockwise or counter-clockwise direction as shown by arrows, I provide a worm gear 33 which is meshed with the teeth at the outer periphery of said spur gear, said worm gear having a shaft 34 extending to a reversible motor, or other suitable power driving means.

Extending from said arm 17 is a supporting bracket 36 which is preferably attached to the cowl of a vehicle, and which further acts as a housing and support for the tubes 15 and 16 and the worm gear 33.

In extending or retracting the signal motive fluid is directed through only one of the two veins created by the communicated passage ways,

depending on the function to be performed. The signal having been extended as shown in Fig. 1 it is set into rotation in a clockwise or counter-clockwise direction to indicate the direction of turn.

What I claim:

1. In a device of the character described, a vertical arm, a shaft extending inwardly and horizontally from the upper portion of said arm, 10 a spur gear rotatably engaging said shaft, inter-central said arm a coupling member in impervious non-rotatable engagement with said gear, a cylinder engaged upon the outer face of said gear, a piston within said cylinder, a piston rod 15 projecting from said cylinder, a signaling member engaging the outer end of said piston rod, continuous passage ways through said device and tubes connecting same with the opposite end portions of said cylinder, a valve arranged to admit motive fluid to said passage ways, whereby the movement of said piston may be controlled and said signal extended or retracted, and power-driven means for rotating said gear, cylinder and signal.
2. A directional signal comprising a flat faced member rotatable a number of revolutions about 20

a horizontal axis in either clockwise or counter-clockwise direction, a signal carried by said member for revolving about said axis with said member, means within the peripheral bounds of said member and fixed against one flat face thereof for operating said signal to extend or retract the same radially of said member during its rotation and means for rotating said member to effect either clockwise or counter-clockwise directional movement thereof and the signal. 5

3. A directional signal comprising a flat faced member rotatable a number of revolutions about a horizontal axis in either clockwise or counter-clockwise direction, a signal carried by said member for revolving about said axis with said member, means within the peripheral bounds of said member and fixed against one flat face thereof for operating said signal to extend or retract the same radially of said member during its rotation, means for rotating said member to effect either clockwise or counter-clockwise directional movement thereof and the signal, and means for controlling the extension and retraction of said signal relative to the rotary member. 10 15 20
